UNITED STATES PATENT OFFICE.

CHARLES A. BRAUNGER, OF ELIZABETH, NEW JERSEY, ASSIGNOR OF ONE-HALF TO
CHARLES HENRY PRUITT, OF CISSNA PARK, ILLINOIS.

IGNITION AND PROPULSION TUBE.

Application filed July 15, 1921. Serial No. 485,059.

To all whom it may concern:

Be it known that I, CHARLES A. BRAUNGER, a citizen of the United States, and a resident of Elizabeth, in the county of Union 5 and State of New Jersey, have invented a new and Improved Ignition and Propulsion Tube, of which the following is a full, clear, and exact description.

This invention relates to an ignition and 10 propulsion tube for bombs or the like.

The object of this invention is to provide in conjunction with a missile containing an explosive charge a device containing means for igniting the explosive charge, means for 15 propelling the missile and operating the igniting means, and means for controlling the flight of the missile.

This object is accomplished by providing a tube containing igniting means for the 20 explosive charge in the missile and that may be operated by a propelling means also contained in the tube and having a guiding means which cooperates with the guide in conjunction with the missile thrower.

25 This and other objects of the invention will be more clearly understood from the following detailed description and accompanying drawings.

Figure 1 is a cross section through the 30 igniting and propelling tube placed in position in a bomb and mounted on the guide in conjunction with the missile thrower; and

Figure 2 is a side elevation of the igniting and propelling tube.

35 Referring to the above-mentioned drawings, 10 is the recoil tube of a missile thrower, described in my copending application, Serial No. 485,058, filed July 15, 1921, and entitled Missile thrower. A projection 40 11 which serves as a guide for controlling the flight of the missile is provided in conjunction with the recoil tube 10. A firing pin 12 is slidably mounted in the opening 13 which extends through the projection 11.

45 A tube 14, which is shown of cartridge shape, has a number of chambers therein. This tube need not be of cartridge shape but this is mentioned as one of the preferred shapes. A chamber 15 is provided in the

50 upper end of the tube for containing a means 16 for igniting the charge 17 contained in the chamber 18, an opening 19 being provided in the end of the tube to connect the chamber 15 to the interior of the bomb.

55 This means for igniting the charge 17 may

consist of quick match, fuse or some other means such as paste that is sometimes used for igniting charges.

Located just below the chamber 15 is another chamber 20. This chamber is for containing the propelling charge, which in this case is shown to be a revolver cartridge 21 having a cap 22. Located in the top of the revolver cartridge is a metal projection 23 which serves to operate the igniting means 65 when the explosion takes place. Any other propelling charge might be used in place of a revolver shell containing explosive but this is mentioned as one of the most convenient charges since it may be prepared by just removing the revolver bullet. Substituting another charge in place of the revolver cartridge it would be necessary to place a detonator in alignment with the opening extending through the projection 11. 70 75

In the base of the tube is a chamber 24. This chamber is so shaped that it fits the projection 11 of the missile thrower and cooperates with the same to direct the flight of the missile. A collar 25 is provided on the 80 base of the tube and the outside portion 26 just above the collar is threaded so as to engage with the threaded opening 27 in the bomb 18.

The operation of this device is as follows: 85

The tube is forced into the bomb containing the explosive charge until the thread 26 has engaged in the threaded opening 27 in the bomb, then, if required, a revolver cartridge which has the bullet removed may be 90 inserted in the chamber 20 and the device is ready for use. When it is desired to fire the bomb the firing pin is withdrawn and the chamber 24 is fitted over the projection 11 of the missile thrower. Proper aim is taken 95 and the firing pin operated by any means to detonate the detonator 22. This explodes the propelling charge in the cartridge 21 which forces the metal projection 23 against the igniting means 16 and operates the same. 100 The igniting means finally ignites the charge and gives the desired explosion. This igniting means may be suited to the required time period.

Claims:

1. In combination with a missile containing an explosive charge, a propulsion and ignition tube of the class described, comprising tube means adapted to be removably inserted into the missile, means for igniting 110

the missile explosive charge carried by the tube, means located in the tube for firing the ignition means, a propelling charge contained in the tube, means operated by the propelling charge to ignite the means for firing the missile explosive charge igniting means, and guiding means in conjunction with the tube.

2. In combination with a missile containing an explosive charge, a propulsion and ignition tube of the class described comprising tube means adapted to be removably inserted into the missile, embedding it in the missile explosive charge, having a chamber therein for receiving a propelling charge, means carried by the tube for igniting the missile explosive charge, means fired by the propelling charge for firing the igniting means, and internal guiding means provided in the tube.

3. In combination with a missile containing an explosive charge, an ignition and propelling tube of the class described, comprising tube means for removably inserting into the missile, having a chamber for the means for exploding the missile charge, a chamber for the means for firing the exploding means, a chamber for the propelling charge, and guiding means enclosed within the base of the tube.

4. In combination with a missile containing an explosive charge, a propulsion and ignition tube of the class described comprising tube means for removably inserting into the missile having a chamber for the means for exploding the missile charge, a chamber for the propelling charge, guiding means enclosed within the base of the tube,

and means for retaining the tube in the missile.

5. In combination with a missile containing an explosive charge, a propulsion and ignition tube of the class described, comprising tube means for removably inserting into the missile to embed the same in the missile explosive charge, means for igniting the missile explosive charge carried by the tube, means located in the tube for firing said igniting means, a propelling charge contained in the tube, means interposed between the propelling charge and said firing means to fire the latter, guiding means in conjunction with the base of the tube, and means for retaining said tube in position in the missile.

6. In combination with a missile containing an explosive charge, a missile thrower having missile guiding means, a propulsion and ignition tube of the class described comprising tube means for removably inserting into the missile to embed in the explosive charge, means for igniting the explosive charge carried by the tube, fuse means located in the tube and associated with the means for igniting the explosive charge, means for firing the fuse, a propelling charge carried by the casing and co-operating with the fuse, firing means to operate the same when the propelling charge is fired, percussion means in conjunction with the propelling charge for firing the same, means for retaining said tube means in position, and means in the base of the tube to serve as guiding means.

CHARLES A. BRAUNGER.

Certificate of Correction.

It is hereby certified that the name of the assignee in Letters Patent No. 1,440,334, granted December 26, 1922, upon the application of Charles A. Braunger, of Elizabeth, New Jersey, for an improvement in "Ignition and Propulsion Tubes," was erroneously written and printed as "Charles Henry Pruitt," whereas said name should have been written and printed as *James Henry Pruitt*, as shown by the records of assignments in this office; and that the said Letters Patent should be read with this correction therein that the same may conform to the record of the case in the Patent Office.

Signed and sealed this 6th day of February, A. D., 1923.

[SEAL.]

KARL FENNING,
Acting Commissioner of Patents.
